UNITED STATES PATENT OFFICE.

JOHN ROGERS FLANNERY AND ETHAN I. DODDS, OF PITTSBURGH, PENNSYLVANIA,
ASSIGNORS TO FLANNERY BOLT COMPANY, OF PITTSBURGH, PENNSYLVANIA.

STAY-BOLT STRUCTURE.

1,298,319.

Specification of Letters Patent. Patented Mar. 25, 1919.

Application filed May 3, 1918. Serial No. 232,295.

To all whom it may concern:

Be it known that we, JOHN ROGERS FLANNERY and ETHAN I. DODDS, citizens of the United States, and residents of Pittsburgh, 5 in the county of Allegheny and State of Pennsylvania, have invented certain new and useful Improvements in Stay-Bolt Structures; and we do hereby declare the following to be a full, clear, and exact description of the invention, such as will enable others skilled in the art to which it app pertains to make and use the same.

This invention relates to improvements in staybolt structures for boilers and more particularly to means for closing the outer end of the bearing sleeve,—the object of the invention being to so connect a cap or closure with a bearing sleeve that it can be quickly removed to permit access to the bolt head 15 for testing purposes, so that it may be as quickly replaced, and so that normally, the cap or closure shall be held tightly to its seat.

With this and other objects in view, the invention consists in certain novel features of construction and combinations of parts as hereinafter set forth and pointed out in the claims.

In the accompanying drawings; Figure 1 30 is a sectional view of a staybolt structure showing an embodiment of our invention; Fig. 2 is a side elevation; Fig. 3 is a transverse section of head on the line 3—3 of Fig. 1; Fig. 4 is a plan view of the bearing sleeve; 35 Fig. 5 is a side elevation of the bearing sleeve; Figs. 6 and 7 are separate views of the cap or closure, and Fig. 8 is a view of a modification.

1 represents a bearing sleeve having a 40 curved interior surface 2 forming a bearing for the head 3 of a staybolt 4,—said sleeve being threaded exteriorly the screw through a boiler sheet, and at its outer end, the bearing sleeve is made with a portion 5 which extends somewhat beyond the threaded portion of the sleeve. The portion 5 of the bearing sleeve is made with laterally projecting segmental shoulders 6 and from each of these, a segmental flange 7 projects outwardly.

In the construction shown in Fig. 1, a cap 10 is seated on the end of the bearing sleeve within the confines of the segmental flanges 7. This cap may have a general hemispheri-

cal shape with its internal dimensions and 55 configuration such as will provide suitable clearance for the head of the staybolt.

The cap or closure 10 is provided with laterally projecting beveled flanges or cams 11 for a purpose hereinafter explained. In 60 the drawings, we have illustrated two such cam flanges located diametrically opposite to each other.

An annular nipple 12 projects from the central portion of the cap or closure 10 and 65 is made to flare somewhat and enter loosely into an annular flaring groove 13 in the central portion of a dome-shaped head or carrier 14,—whereby the cap and carrier are loosely connected together so that the cap 70 may have sufficient movement to the carrier (a clearance space 15 being provided between them) to permit said cap to compensate for slight inequalities in its bearing face or its seat.

The head or carrier 14 incloses the cap 10 and is made with a peripheral portion 16 (having an angular or hexagonal outer face for the accommodation of the wrench), which encircles the outer end portion of the 80 bearing sleeve and is provided with inwardly projecting segmental lips or shoulders 17 to engage behind the segmental shoulders 6 on the bearing sleeve.

The head or carrier 14 is provided internally with segmental beveled shoulders 18, between which and the shoulders 6 on the bearing sleeve, the beveled flanges or cams 11 on the cap will be disposed when the parts are in their normal positions, and the said 90 cam flanges 11 will be disposed in the spaces formed between the flanges 7 to prevent the cap 10 from turning. It will be observed that there is a slight clearance space 19 between the cam flanges 11 of the cap and the 95 shoulder 6 on the bearing sleeve.

The assembled cap 10 and head or carrier 14 will be placed on the extended end of the bearing sleeve and the head or carrier 14 will then be turned with the use of a suitable 100 wrench. The head or carrier will turn relatively to the cap and the segmental shoulders therein 17 will become disposed behind the segmental shoulders 6 on the bearing sleeve. At the same time, the coöperation 105 of the shoulders 18 in the head with the cams 11 on the cap will serve to press the latter tightly upon its seat and cause the

shoulders 17 to bind against the shoulders 6, and thus the cap or closure will be held firmly in place.

By turning the head or carrier in the reverse direction, the cap and its carrier will become promptly released from the bearing sleeve and may be quickly removed to expose the head of the bolt for testing purposes. It is apparent that cap or closure can 10 be as quickly replaced and locked in position on the bearing sleeve.

Instead of making the portion 5 as an integral part of the sleeve, it may be made as a separate collar 8 threaded internally to 15 screw on the sleeve, as shown in Fig. 8,—said collar having the segmental shoulders 6 and flanges 7 and also having an inwardly projecting annular flange 9 overlying the end of the bearing sleeve, said flange serving 20 as a cap seat.

Having fully described our invention what we claim as new and desire to secure by Letters-Patent, is:—

1. In a staybolt structure, the combination 25 with a bearing sleeve, of a head, means removably connecting said head with the bearing sleeve, a cap or closure for the bearing sleeve inclosed within said head, lateral cams on said cap or closure, and shoulders within 30 the head to be disposed over the lateral cams of the cap or closure and coöperable with the same.

2. In a staybolt structure, the combination 35 with a bearing sleeve having segmental shoulders, and a cap or closure having laterally projecting cams, of a head or carrier in which said cap or closure is disposed, said head having segmental shoulders to engage the segmental shoulders on the bearing 40 sleeve, and said head being shouldered internally to coöperate with the laterally projecting cams on the cap.

3. In a staybolt structure, the combination

with a bearing sleeve having segmental flanges, and a cap to seat on the bearing 45 sleeve and having laterally projecting cams, of a head or carrier inclosing said cap and having segmental shoulders to engage the segmental shoulders on the bearing sleeve, said head having segmental shoulders there- 50 in to coöperate with the cams on the cap, and means loosely connecting the cap with the central portion of the carrier.

4. In a staybolt structure, the combination 55 with a bearing sleeve having lateral segmental shoulders and segmental flanges on said shoulders, and a cap or closure having lateral cams to enter between said segmental flanges, of a head inclosing said cap or closure and having segmental shoulders to en- 60 gage the shoulders on the bearing sleeve, said head having segmental shoulders adapt- ed to coöperate with the lateral cams on the cap or closure.

5. In a staybolt structure, the combination 65 with a bearing sleeve, of a head or carrier means effecting a removable connection of said head or carrier with the bearing sleeve, said head or carrier having an annular flaring groove centrally located therein, a cap 70 or closure inclosed within said head and having an annular projection loosely entering the flaring groove in said head or carrier, lateral cams on the cap or closure, and segmental shoulders in the head or carrier 75 to coöperate with said last-mentioned seg- mental shoulders.

In testimony whereof, we have signed this specification in the presence of two subscr- 600
ibing witnesses.

JOHN ROGERS FLANNERY.
ETHAN I. DODDS.
